CLAIM

The ornamental design for a combined drainer and bowl, as shown and described.

DESCRIPTION

FIG. 1 is a top perspective view of a combined drainer and bowl showing my new design;

FIG. 2 is a front view thereof;

FIG. 3 is a rear view thereof;

FIG. 4 is a right view thereof;

FIG. 5 is a left side view thereof;

FIG. 6 is a top view thereof;

FIG. 7 is a bottom view thereof;

FIG. 8 is an exploded front perspective view thereof;

FIG. 9 is a bottom view thereof, shown without the drainer and the bowl for clarity of disclosure;

FIG. 10 is a top thereof, shown without the lid and the bowl for clarity of disclosure;

(Continued)

FIG. 11 is an exploded front view thereof;
FIG. 12 is an exploded rear view thereof;
FIG. 13 is an exploded right side view thereof; and,
FIG. 14 is an exploded left side view thereof.
